UNITED STATES PATENT OFFICE.

WILLIAM HARRY RAY, OF CHICAGO, ILLINOIS, ASSIGNOR TO WESTERN ELECTRIC COMPANY, INCORPORATED, OF NEW YORK, N. Y., A CORPORATION OF NEW YORK.

FORMING APPARATUS.

Application filed December 1, 1924. Serial No. 753,067.

This invention relates to forming apparatus, and more particularly to forming apparatus comprising dies movable into pressing engagement with each other.

5 The object of the invention is to provide improved apparatus for forming articles from flexible material.

One embodiment of the invention is particularly adapted to form cones for loud speakers of the type shown in the copending application of Norman H. Ricker, Serial No. 592,675, filed October 6, 1922. This embodiment of the invention comprises two die members movable into pressing engagement 15 with a relatively fixed die member to form a cone of the character described from a paper blank, one of the movable members being pivoted to a lever pivotally secured to the other movable die member which is in turn 20 pivotally secured to the fixed die member. One of the movable die members cooperates with the fixed die member to form a seam of two edges of the blank to which an adhesive substance has been applied, cam 25 means associated with the lever being operable to exert increased pressure on these edges when the dies are in pressing engagement with each other.

Other features of the invention will be 30 come apparent as the detailed description progresses, reference being had to the accompanying drawings, wherein

Fig. 1 is a plan view of apparatus embodying the invention;

35 Fig. 2 is a section taken on line 2—2 of Fig. 1;

Figs. 3 and 4 are sections taken on lines 3—3 and 4—4, respectively, of Fig. 2;

40 Fig. 5 is a section taken on line 5—5 of Fig. 1;

Fig. 6 is a plan view of a blank from which the improved apparatus is adapted to form a cone;

Fig. 7 is a side elevation of a cone formed 45 from a blank similar to that shown in Fig. 6;

Fig. 8 is a plan view of a blank from which the improved apparatus is adapted to form a frusto-conical article, and

50 Fig. 9 is a side view of a frusto-conical article formed from a blank similar to that shown in Fig. 8.

The apparatus shown in Figs. 1 to 5, inclusive, is adapted to form the cones employed

in the manufacture of loud speakers of the type shown and described in the above referred to application. The cones are formed from blanks of paper 10 and 11 which are shown in Figs. 6 and 8, respectively. The blank 10 is substantially circular in form, a segment thereof being removed to form two opposed edges 13 and 14 which are skived for a purpose which will presently appear. The center of the blank 10 is indicated by a relatively small aperture 15. The blank 11 is substantially ring-shaped in form, a segment thereof having been removed to form two opposing edges 18 and 19 which are skived in the same manner as the edges 13 and 14 of the blank 10.

Referring now to Figs. 1 to 4, inclusive, 70 25 designates generally a die member adapted to rest upon any suitable support as, for instance, a table 26. The die member 25 has a conical surface 27, from the apex of which projects a pin 28. A plurality of holes 30 75 drilled into the conical surface 27 are adapted to receive pins 31 carrying stop members 33, the stop members 33 being shown in dotted lines in Fig. 1 and being shown in full lines in Fig. 5. Formed integral with the 80 die member 25 are lugs 35 carrying a pin 36, the purpose of which will presently appear.

Pivoted secured to the die member 25 by a pin 38 is one end of an arm 39 provided with bifurcations 40 at its free end. A pin 41 passed through suitable apertures formed in the bifurcations 40 is rigidly secured to the bifurcations by taper pins 42. Secured to the pin 41 by a taper pin 43 is a lug 44 forming part of a die member 45 provided with a recessed conical surface 46 adapted to cooperate with the conical surface 27. A gasket 49 of resilient material is fitted snugly into an arcuate groove 50 cut into the conical surface 46.

Pivoted upon the pin 41 is a bifurcated lever 52 which carries a die member 54, the die member 54 being pivotally secured to the lever by a pin 55 and being adapted to pass through a slot 56 in the die member 45. 100 Angular displacement of the die member 54 around the axis of the pin 55 is limited by pins 58 projecting from the lever 52. The die member 54 is provided with a surface 60 which may be aligned with the surface 46 105 to form a continuation thereof.

Pivots secured to the lever 52 by a pin 62 is a cam member 64 which is provided with a handle 65 and with a cam surface 66 adapted to engage the pin 36 when the die members 45 and 54 are in the positions wherein they are shown in full lines in Fig. 2. The cam surface 66 is so designed that when the cam member 64 is angularly displaced in a counter-clockwise direction (Fig. 2) the die members 45 and 54 are urged toward the die member 25, the construction being such that the pressure exerted between the surfaces 60 and 27 will be greater than the pressure exerted between the surfaces 46 and 27.

The die members 45 and 54 may be swung into the positions wherein they are shown in dotted lines in Fig. 2. The die member 45 is shown in the position wherein a lug 68 formed upon the arm 39 engages a lug 69 formed upon the die member 25 and prevents further displacement of die member 45. The die member 54 is shown in an intermediate position, but may be brought into a position wherein lugs 70 formed integral with the lever 52 engage lugs 72 formed integral with the arm 39.

When a cone is to be formed from a blank 10, adhesive is applied to the edges 13 and 14 of the blank and it is placed upon the conical surface 27 in such manner that the pin 28 projects through the aperture 15 and the edges 13 and 14 lie in the path of die member 54. The die members 45 and 54 are then brought into pressing engagement with the die member 25, the operator using care to see that the edges 13 and 14 properly meet and engage each other. The operator then presses downwardly upon the handle 65 and causes the cam surface 66 to engage the pin 36 and to advance transversely thereof until sufficient pressure is exerted between the die members 54 and 25 to insure that the skived edges 13 and 14 will form a perfect seam. The blank is locked in the apparatus by means of the cam member 64 until the skived edges 13 and 14 are firmly attached to each other and then the die members 45 and 54 are swung into the positions wherein they are shown in Fig. 2 to permit removal of the finished cone from the apparatus.

When the frusto-conical article shown in Fig. 9 is to be formed from the blank 11, the stops 33 are properly placed upon the conical surface 27. The blank 11 is then fitted around the conical surface in such manner that its outer edge is engaged by the stops as illustrated in Fig. 5 and in such manner that the skived edges 18 and 19 properly engage each other in the path of the die member 54, a suitable adhesive having been applied to the edges. The die members 45 and 54 are then brought into pressing engagement with the die member 25 in substantially the same manner as when a

cone is being formed from a blank 10. After the blank 11 has been subjected to pressure for the proper length of time the die members 45 and 54 are brought into positions wherein they are shown in dotted lines in Fig. 2 and the fully formed frusto-conical article is removed from the apparatus.

What is claimed is:

1. An apparatus for forming an article from a circular piece of material having a cut-out sector, comprising means for bringing the edges of the cut-out portion together, and means for exerting a pressure along said edges.

2. In forming apparatus; a die member, a second die member, a lever pivoted to the second die member, and a third die member carried by the lever, the second member and the third member being movable into positions wherein they are simultaneously in pressing engagement with the first member.

3. In forming apparatus, a die member, a second die member pivotally secured to the first die member, a lever pivoted to the second die member, and a third die member pivoted to the lever, the second member and the third member being movable into positions wherein they are simultaneously in pressing engagement with the first die member.

4. In forming apparatus, a die member, a second die member pivotally secured to the first die member, a lever pivoted to the second die member, and a third die member pivoted to the lever, the second member and the third member being movable into positions wherein they are simultaneously in pressing engagement with the first die member, and means associated with the lever for exerting increased pressure between the third member and the first member.

5. In forming apparatus, a die member, a second die member pivotally secured to the first die member, a lever pivoted to the second die member, and a third die member pivoted to the lever, the second member and the third member being movable into positions wherein they are simultaneously in pressing engagement with the first die member, and cam means associated with the lever for exerting increased pressure between the third member and the first member.

6. In forming apparatus, a die member, a second die member, a third die member, means for bringing the second member and the third member into pressing engagement with the first member, and means for exerting greater pressure between the first member and one of said other members than between the first member and the remaining member.

7. In forming apparatus, a die member, a second die member, a third die member, means for bringing the second member and the third member into pressing engagement

with the first member, and cam means for exerting greater pressure between the first member and one of said other members than between the first member and the remaining member.

8. In forming apparatus, a die member, a second die member, a third die member, means for bringing the second member and the third member into pressing engagement with the first member, and means carried by one of the members for exerting greater pressure between the first member and one of said other members than between the first member and the remaining member.

15 9. Forming apparatus comprising means for holding material in a position to form a cone wherein the surfaces of two edges thereof are in close proximity to each other, and separate means for applying pressure to the material to urge the surfaces of the edges against each other.

20 10. Forming apparatus comprising means for holding material in a position to form an article wherein the surfaces of two edges thereof are in close proximity to each other, and cam operated means for applying pres-

sure to the material to urge the surfaces of the edges against each other.

11. In forming apparatus, the combination with a die member, of a second die member cooperating with first die member to hold material in a position to form an article wherein the surfaces of two edges thereof are in close proximity to each other, and means movable relatively to the die members and engageable with the material for urging the surfaces of the edges against each other.

12. In forming apparatus, the combination with a die member, of a second die member cooperating with the first die member to hold material in a position wherein two edges thereof are in close proximity to each other, and a third die member cooperating with one of the other die members for urging the surfaces against each other.

In witness whereof, I hereunto subscribe my name this 17th day of November, A. D. 1924.

WILLIAM HARRY RAY.
